UNITED STATES PATENT OFFICE

161,446

GLOVE

Julius A. Higier, Johnstown, N. Y., assignor to
Crescendoe Gloves, Inc., Johnstown, N. Y., a
corporation of New York

Application January 20, 1950, Serial No. 7,357

Term of patent 3½ years

(Cl. D3—11)

To all whom it may concern:

Be it known that I, Julius A. Higier, a citizen of the United States of America, residing in Johnstown, county of Fulton, and State of New York, have invented a new, original, and ornamental Design for a Glove, of which the following is a specification, reference being had to the accompanying drawing, forming part thereof.

Figure 1 is a rear elevational view of a glove, showing my new design.

Figure 2 is a front elevational view of the glove shown in Figure 1, drawn on a smaller scale.

The rear faces of the petal-like members are of contrasting appearance to the front thereof.

I claim:

The ornamental design for a glove, substantially as shown and described.

JULIUS A. HIGIER.
